(57) **CLAIM**

The ornamental design for a food container array, as shown and described.

DESCRIPTION

FIG. 1 is a top perspective view of the first and second embodiments of the food container array of the present invention;

FIG. 2 is a left elevation view of the first and second embodiments of the food container array of the present invention, with the right elevation view a mirror image of the left elevation view;

FIG. 3 is a front elevation view of the first and second embodiments of the food container array of the present invention, with the rear elevation view a mirror image of the front elevation view;

FIG. 4 is a top elevation view of the first and second embodiments of the food container array of the present invention;

FIG. 5 is a bottom perspective view of the first embodiment of the food container array of the present invention; and,

FIG. 6 is a bottom perspective view of the second embodiment of the food container array of the present invention.

With respect to the first embodiment, the broken line circles at the base of each container as shown in FIG. 5 represent the bounds of the claimed design, and form no part of the claimed design.

The broken lines shown in FIGS. 1, 4, 5, and 6 represent perforations.
